UNITED STATES PATENT OFFICE.

JOHN O'NEIL, OF WILMERDING, PENNSYLVANIA.

RAIL-FASTENER AND LOCK.

No. 872,743.

Specification of Letters Patent.

Patented Dec. 3, 1907.

Application filed June 28, 1907. Serial No. 381,308.

To all whom it may concern:

Be it known that I, JOHN O'NEIL, a citizen of the United States of America, residing at Wilmerding, in the county of Allegheny and State of Pennsylvania, have invented certain new and useful Improvements in Rail-Fasteners and Locks, of which the following is a specification, reference being had therein to the accompanying drawing.

10 This invention relates to improvements in rail fasteners and locks, and the invention has for its object to provide a simple and inexpensive rail fastener for preventing a rail from being laterally displaced upon a tie or 15 rail support.

Another object of this invention is the provision of positive and reliable means for preventing the parts of the rail fastener from being separated, said means being protected 20 from water, dirt and such matter as would tend to injure the same.

A further object of this invention is to provide a novel rail fastener that can be used for retaining the confronting ends of two 25 rails together.

With the above and other objects in view, which will more readily appear as the invention is better understood, the same consists in the novel construction, combination and 30 arrangement of parts to be presently described, and then specifically pointed out in the appended claims.

In the drawings, Figure 1 is a perspective view of the rail fastener, and Fig. 2 is a cross 35 sectional view of the same.

The rail fastener embodies a chair comprising a base plate 1 having an integral splice bar 2, adapted to embrace the inner sides of rails 3. The chair 1 can be placed 40 upon the top of the tie 4 or similar support, or can be partially embedded in the same, as at 5.

The outer sides of the rails 3 are embraced by a splice bar 6, said splice bar being recessed, as at 7 and 8, and secured to the base plate 1 by vertically disposed bolts 9 and nuts 10. The heads 11 of the bolts 9 are countersunk in the base plate 1, while the nuts 10 are retained upon the bolts 9 by a 50 plate 12, hinged, as at 14, to seat in the recess 8 of the splice bar 6. The hinged plate 12 is provided with a conventional form of lock 15 manipulated by a key 16 entering a key opening or hole 17. The latch 18 of the 55 lock 15 engages in a latch opening 19 formed

in the vertical wall of the splice bar 6, said latch retaining the hinged plate 12 in a closed position, preventing the nuts 10 from being surreptitiously or accidentally removed from the ends of the bolts 9. 60

Protecting the lock casing 15 from dirt and water is a hinged shutter 20, pivoted upon the plate 12, as at 21, in close proximity to the key opening or hole 17. The outer edge of the splice bar 6 is recessed, as at 22, 65 to receive the heads of spikes 23 employed for holding the outer edge of the splice bar 6 and the base plate 1 upon the tie 4.

From the novel construction of my improved fastener, it will be observed that the 70 nuts 10 of the bolts 9 cannot become entirely disengaged from the bolts 9 due to vibrations of the rails 3, when rolling stock is passing over said rails. By unlocking the plate 12 easy access can be had to the nuts, 75 when it is desired to remove the splice bar 6 and renew the rails 3, it of course being understood that the spikes 23 can be removed also.

The fastener in its entirety is made of 80 strong and durable metal and various types of locks can be used for securing the hinged plate of the fastener in a closed position.

Having fully described my invention, what I claim and desire to secure by Letters 85 Patent is:

1. In a rail fastener, the combination with rails and a support, of a chair carried by said support, comprising a base plate and a splice bar for engaging the inner sides of said rails, 90 a splice bar resting upon said base plate and embracing the outer sides of said rails, bolts extending upwardly through said base plate and splice bar, said splice bar having recesses formed therein, nuts secured upon said bolts in one of said recesses, a plate hinged to said splice bar and seating in the other of said recesses, a lock carried by said hinged plate and having a latch to engage in said splice bar, said plate having a key opening formed therein, a shutter for normally closing said opening, and means for securing said chair and splice bar to said support. 95

2. In a rail fastener, the combination with rails, of a chair, for embracing the inner sides and bottom of said rails, a splice bar mounted upon said chair and embracing the outer sides of said rails, bolts and nuts for holding said splice bar upon said chair, a plate hinged to said splice bar and covering said nuts, a 110

lock carried by said plate and engaging said splice bar for holding said plate in a closed position.

3. In a rail fastener, the combination with 5 rails, of a chair for embracing the inner sides and base of said rails, a splice bar mounted upon said chair and embracing the outer sides of said rails, means for holding said splice bar in engagement with said chair, and

a hinged plate carried by said splice bar for 10 shielding and covering said means.

In testimony whereof I affix my signature in the presence of two witnesses.

JOHN O'NEIL.
